UNITED STATES PATENT OFFICE

ANDREW SHIELDS, OF HAMDEN, CONNECTICUT, ASSIGNOR TO THE AMERICAN MILLS COMPANY, OF WATERBURY, CONNECTICUT, A CORPORATION

DESIGN FOR A STRIP OF WEBBING OR SIMILAR MATERIAL

Application filed September 3, 1929. Serial No. 32,658. Term of patent 3½ years.

To all whom it may concern:

Be it known that I, ANDREW SHIELDS, a citizen of the United States, residing at Hamden, in the county of New Haven and State of Connecticut, have invented a new, original, and ornamental Design for a Strip of Webbing or Similar Material, of which the following is a specification, reference being had to the accompanying drawing, forming part thereof.

The figure is a face view of a strip of webbing or similar material showing my new design.

I claim:

The ornamental design for a strip of webbing or similar material as shown.

ANDREW SHIELDS.
